UNITED STATES PATENT OFFICE.

ALEXANDER H. HYNDMAN, OF CHICAGO, ILLINOIS.

MAGNETO.

1,407,421.

Specification of Letters Patent. Patented Feb. 21, 1922.

Application filed November 16, 1918. Serial No. 262,811.

To all whom it may concern:

Be it known that I, ALEXANDER H. HYNDMAN, a citizen of Canada, residing at Chicago, in the county of Cook, State of Illinois, have invented certain new and useful Improvements in Magnetos, of which the following is a specification.

The present invention relates to magnetos and has to do more particularly with the armatures of such machines. The principal objects of the invention are: (1) to cheapen the cost of manufacture, (2) to provide a construction such that more turns of wire can be obtained with the same armature diameter than is possible in prior structures, (3) to make the parts unitary so that they may be readily assembled in manufacture and readily removed and replaced by duplicate parts for the purpose of repair, (4) to provide a construction which can be used in manufacturing armatures for use with alternating currents of high, low or intermediate voltages, (5) to provide a construction in which the electrical windings may be wound directly upon the core by hand or wound as separate units upon forms or in winding machines, (6) to provide a construction such that the core and windings may be readily multiplied to provide larger machines, and (7) to provide other features and advantages in details and arrangement of parts.

The various features and advantages of my invention will be more fully understood upon reference to the following detailed description taken in connection with the accompanying drawing, while the scope of the invention will be particularly pointed out in the appended claims.

In said drawing, Fig. 1 is a perspective view of a magneto armature constructed in accordance with the present invention; Fig. 2 is a central longitudinal section of the same taken through the center of the pole pieces; Fig. 3 is a transverse section of the same taken on a plane indicated by the line 3—3 of Fig. 2; Fig. 4 is a perspective view of one of the unitary electric coils; Fig. 5 is a partial longitudinal section similar to Fig. 2 illustrating a laminated core structure; Fig. 6 is a transverse section corresponding to a section through the axis of the core of the structure of Fig. 2 illustrating a modification in which the pole pieces and shaft are cut away so as to provide an enlarged space for the windings of the coil; Fig. 7 is a similar trans-

verse sectional view of a further modification showing a laminated core and light arcuate pole pieces which cooperate to provide a large winding space; Fig. 8 is a central longitudinal section similar to that of Fig. 2 illustrating a further modification in which two cores with their pole pieces and windings are mounted on the same shaft; Fig. 9 is a similar central longitudinal section of a further modification in which the journals of the armature are secured to end plates instead of to the core as in previous figures; Fig. 10 is an end elevation of said structure, and Fig. 11 is a sectional view illustrating the structure of Fig. 2 but providing different means for securing the pole pieces to the cores. Throughout these views like characters refer to like parts.

Referring to the drawing in detail, and more particularly at first to the form of the invention illustrated in Figs. 1 to 4 inclusive, 10 designates the shaft of the armature which is adapted to be mounted in bearings formed in the frame of the magneto. Any desired frame structure may be employed and as the same forms no part of the present invention, I have not illustrated it. The journals which rest in the bearings are formed near the ends of the shaft and are designated 11 and 12. The rings 13 and 14 adjacent to these bearings are the usual oil supplying rings for bringing oil to the journals 11 and 12. The shaft also carries the usual current collecting ring 15 which is located upon the periphery of an insulating disk 16. The parts thus far described are well known parts and need not be set forth in further detail.

The core 17 is mounted upon the shaft 10 at a point intermediate of the journals 11 and 12 and is positioned so that its axis extends at a right angle to the axis of the shaft 10 which is obviously also the axis of the entire armature structure. In the present instance the core is a solid piece of soft iron. It is provided at its center with a transverse hole which is just large enough to receive the reduced portion of the shaft. The disk 16 and an associated ring 14 are put in place and are secured in any suitable way, as by a driving fit.

The opposite ends of the core 17 are provided with pole pieces 18 and 19. These pole pieces, like the core 17, are solid and composed in each instance of soft iron. The outer surface of each is a cylindrical surface

having for its axis the axis of the armature. The inner faces are plane faces which abut against and cover the ends of the core 17. The pole pieces over-hang the core 17 on all 5 sides. The shaft 10, core 17 and pole pieces 18 and 19 are preferably all secured together by a pin or rod 20 which extends through holes drilled through these parts, and is riveted at its ends to the pole pieces 10 18 and 19. The holes in the latter through which the rod passes are preferably counter-sunk, so that when the ends of the rod 20 are struck up so as to provide the rivet heads, none of the metal of the rod will extend 15 beyond the cylindrical faces of the pole pieces. In the present instance, I also provide two screws 21 for further securing the pole piece 18 to the core 17. Screws 22 perform a like function for the pole piece 19. 20 All of these screws pass into threaded engagement with openings in the ends of the core 17. The openings in the pole pieces through which they pass are counter-sunk so that the top of the screw lies flush with 25 the cylindrical surface of the pole pieces. In order to prevent each screw from working loose, I preferably drill a small hole through the head of the screw and into the pole piece and drive a small pin into the 30 same as indicated at 23 in Figs. 1 and 2. Obviously, the pole pieces, core and shaft might be connected differently than I have illustrated. Thus, in certain instances, the screws 21 and 22 might be omitted and the 35 riveted rod 20 relied upon to hold the parts together. In other instances, the screws might be employed and the rod might be omitted, and in still other instances, the core and shaft might be connected together 40 by other means.

In the form of the invention under consideration, two sets of windings are employed. These are in the forms of coils 45 24 and 25 which occupy the space between the shaft 10 and the overhanging portions of the pole pieces 18 and 19, respectively. Obviously, these windings may be wound upon the core 17 after the pole pieces have been secured in place. The turns of insulated wire are separated from the adjacent 50 portions of the pole pieces, core and shaft by insulation, the insulation 26 serving in the case of coil 24, and the insulation 27 serving in the case of coil 25. Although the 55 windings may be wound in this way, yet I prefer to make each of the coils a separate unitary structure which may be wound independently of the other parts of the armature and kept in stock for assembling with 60 the other parts in the original manufacture or for replacing defective coils when the armature needs repair. Such a unitary coil is shown in Fig. 4, where the winding 24 is located upon insulation 26, which has the 65 form of a spool. These units can be made

up in various ways, as by winding the insulated conductor upon forms and then placing the completed coil upon the shank of the spool of insulating material and then applying either or both of the end flanges of 70 the spool, or the coils may be wound either independently of the spool or upon it by suitable winding machines. The terminals of the coils 24 and 25 may be connected in any suitable way, thus for example, the one 75 terminal may be connected to the collecting ring 15, as indicated at 28, and the other may be connected to some portion of the iron structure of the armature such as the pole piece 18, as indicated at 29. The coils 80 themselves may obviously be connected together in series or in multiple. These various connections are well known and need not be further gone into in this description.

In case it becomes necessary to replace 85 one of the windings of the armature just described, it is merely necessary to remove the adjacent pole piece, disconnect the terminals of the coil, withdraw the coil from the core, place the new coil in position, restore the pole piece and connect the coil terminals in circuit. In removing the pole piece it will be necessary to destroy the rivet head of the rod 20 so as to drive the 90 rod out and it will also be necessary to free 95 the screws which pass through the pole piece. The latter can be done by drilling out the pin 23. Likewise, the head of the rod 20 may be removed by drilling.

From this description it will be seen that 100 the pole pieces 18 and 19 are removable from the core 17 and yet they are not so readily removable that they can be dislodged or loosened under the continued rotation of the armature nor by simple manipulation on 105 the part of the user. They can, however, be removed by a repair man without much difficulty. The construction provides a considerable advantage in this respect because the coils can be so readily removed and new 110 ones put back into place. By having the coils upon independent spools and in stock it is not necessary to take the time of a workman to unwind the wire of the defective coil and then wind the wire of the new 115 coil on the core. It will be noted that in this construction the polar extensions formed by the over-hanging portions of the pole pieces 18 and 19 serve to hold the coils 24 and 25 in place against any tendency to be 120 dislodged by centrifugal force.

Obviously either the core or pole pieces or both the core and pole pieces may consist of laminations of soft iron instead of 125 consisting of solid pieces as heretofore described. In Fig. 5, I have illustrated a core 30 which is made up of laminations held together by riveting rods, of which one, designated 31, is shown. In this instance, the pole piece is made up of solid ends 32 and 130

intervening laminations 33 which are held together by transverse riveting rods, one of which, designated 34, is shown. The pole pieces, armature and shaft are all secured together by a rod 35 and the pole piece and core are further secured together by screws 36. This structure is similar to that shown in Fig. 2 but differs in the employment of laminations instead of solid metal. The illustration of Fig. 5 is fragmentary but is sufficient to illustrate the substitution of a laminated structure for the solid structure.

As a further modification I may cut away a portion of the shaft on either side and also cut away a portion of the under face of each of the pole pieces, all of which is to provide a greater space for the windings of the associated electric coils. Such a modification will be sufficiently illustrated by Fig. 6 wherein the shaft 36 is shown cut away on its upper and lower faces and the pole pieces 37 and 38 are shown cut away on their inner faces. These parts are the same as the corresponding parts of Fig. 1, except for the modifications mentioned. In this instance the space between the shaft 36 and the over-hanging portions of the pole piece 37 are occupied by coils 39 and 40. Suitable insulation 41 separates these coils from each other and from the adjacent portions of the shaft, core and pole piece. In this instance the core 42 is the same as the core 17 except that it is provided with a differently shaped opening for the passage of shaft 36. Similar coils 43 and 44, provided with insulation 45, are positioned between the shaft 36 and the pole piece 38. These coils may be variously connected and particular connections need not be specified. With this arrangement the place available for the electric windings of the coils is greater than in the form of the invention illustrated in Figs. 1 and 2 and yet the cylindrical faces of the pole pieces 37 and 38 remain the same in superficial extent.

The shape of the pole piece may be still further modified by constructing the same out of a piece of thin light magnetic material, preferably arcuate in form. Such construction is illustrated in Fig. 7, in the pole piece 46. In this figure, also, I have shown the core 47 as composed of laminations connected by riveting rods 48. In this instance, the end of the core 47 is curved to conform to the inner face of the pole piece 46, and the pole piece and core are secured together in any suitable way as by the screw 49. The members 50 are sheets of metal provided with central perforations and slipped over the core. They cooperate with the pole piece 46 to provide space for the electric windings 51. These windings are separated from the pole piece 46, core 47 and member 50 by suitable insulation. Obvi-

ously in this construction, the core 47 might consist of a solid piece of magnetic material the same as in the form of the invention illustrated in Figs. 1 and 2. In this instance, the space provided for the coil 51 is very large 70 and the superficial area of the pole pieces is not decreased.

In still other instances, the capacity of the magneto may be such as to require an increased winding space and an increased magnetic circuit. In such instances, I may increase the capacity by multiplying the structure of Figs. 1 and 2 so as to provide a plurality of cores with their pole pieces and windings. Such a structure is illustrated in Fig. 8 80 wherein the shaft 53 is provided with cores 54 and 55 of the same construction as shown in Figs. 1 and 2. In this instance the core 54 is provided with energizing coils 56 and 57 while the core 55 is provided with similar 85 coils 58 and 59. In this instance, the two cores are provided with common pole pieces 60 and 61 and the parts are secured together by rods 62 and 63 and screws 64 and 65 in a manner similar to that disclosed with 90 reference to Figs. 1 and 2. In this instance the insulation about the coils is designated by the numerals 66, 67, 68 and 69.

In still other forms of the invention, the journals 70 and 71 of the armature may be 95 directly secured to heads 72 and 73 which are in turn secured to the opposite ends of pole pieces 74 and 75 while the latter are secured to the opposite ends of a core 76. In this instance, it will be seen that the core 100 has no direct connection with the armature shaft but the latter is divided in the manner illustrated. In this instance, the core 76 is connected with the pole pieces 74 and 75 by a rod 77 and screws 78 and 79 in the 105 manner heretofore described. In this instance the heads 72 and 73 are secured to the pole pieces 74 and 75 by pins 80, 81, 82 and 83 which extend through openings in the heads into engagement with holes tapped 110 into the ends of pole pieces. In this form of the invention, the windings fill the entire space between the pole pieces 74 and 75 around the core 76. In the present instance an inner coil 84 and an outer coil 85 with 115 suitable insulation 86 intervening and separating the coils from the pole pieces and core, constitute the windings. A suitable electric terminal is provided by a pin 87 riveted to the center of a spring plate 88 which is secured at its ends to the inner face of the head 72 by screws 87^a and 88^a. The shaft is hollowed out for the passage of the pin 87 and suitable insulation 89 and 90 protects the conducting plate and pin from engagement 120 with the head and shaft. The terminals of the coils 84 and 85 may be connected in any desired way and the appropriate connections made with the plate 88 by soldering or otherwise. In the present illustration, 130

one terminal of the coil 85 is shown soldered to the head 73 at the point 89^a and the other to the plate 88 at 90^a. Such a connection will suffice where the windings of coils 84 5 and 85 are primary and secondary windings respectively.

As illustrative of modified connecting means between the pole pieces and core, I have added Fig. 11 wherein the core 17 and 10 pole piece 18 of Fig. 2 are illustrated in connection with a rod 91 which extends through them and the connecting shaft as in Fig. 2 but which instead of being riveted as in Fig. 2 is 15 electrically welded by the deposition of metal as indicated at 92 where the electrically deposited welding metal is shown in a socket or counter-sunk opening. As there shown, it does not extend beyond the face of the pole piece 18. Obviously, other connecting means 20 might be employed for securing these various parts together with sufficient certainty to guarantee their remaining in position until taken in hand by the repair man. Likewise, in these constructions, the core may be 25 greatly varied in cross-sectional shape. Obviously too, the windings upon the armature may in many instances be primary and secondary windings variously connected and associated. The construction provided 30 retains all the advantages possessed by prior art devices in respect to the electrical connections of the various windings of the coils. I may also point out that other means may be employed for holding the screws in the 35 pole piece against rotation than the pins 23 heretofore described. Such means may be in addition to or a substitute for these pins. In the form of the invention illustrated in Fig. 1, such additional means are provided by the 40 heads of the rod 20. The countersinks provided at the ends of the hole for the rod 20 and those provided for the screws 21 and 22 are made to overlap. By countersinking the 45 holes for the rod after the screws are set, a portion of the head of each screw is cut away. Then when the end of the rod is 50 welded or riveted, the metal of the rivet head enters the space produced by cutting away portions of the screw heads and thus provides an interlock with the screws that 55 prevents their rotation. When repairing, the rod heads are cut away as before described and the screws can then be removed. In reassembling a new rod and the same or new screws may be used.

What I claim as new and desire to secure by Letters Patent of the United States, is:

1. A magneto armature comprising a

transversely apertured core of magnetic material, a shaft extending through and closely fitting within the aperture in said core, the axes of said core and said shaft intersecting each other at right angles, the shaft having flat portions on its opposite sides and on opposite sides of and close to said core, said portions lying in parallel planes perpendicular to the axis of said core, pole pieces of magnetic material secured to the opposite ends of said core and overhanging the same on all sides and having in each instance an outer cylindrical surface and a plurality of inner plane faces lying in planes parallel to the flat portions of said shaft, said inner plane faces on each pole piece comprising a central face contiguous to the core and a peripheral face more distant therefrom, the central faces of both pole pieces being coextensive in superficial area and lying equidistant from said shaft and farther therefrom than the peripheral faces, and two electric coils fitting closely about said core on opposite sides of said shaft and completely filling in each instance the space between the central inner face on the pole piece and the co-operating flat portion on the shaft, said pole 85 pieces being removable from said core to allow said coils to be removed as units from said core.

2. A magneto armature comprising a transversely apertured core of magnetic material, a shaft extending through and closely fitting within the aperture in said core, the axes of said core and said shaft intersecting each other at right angles, pole pieces of magnetic material secured to the opposite 90 ends of said core and overhanging the same on all sides and having in each instance an outer cylindrical surface and a plurality of inner plane faces lying in parallel planes perpendicular to the axis of said core, said inner plane faces on each pole piece comprising a central face contiguous to said core and a peripheral face more distant therefrom, the central faces of both pole pieces being of the same superficial area and lying equidistant from said shaft and farther therefrom than the peripheral faces, and two electric 95 coils closely fitting about said core on opposite sides of said shaft and completely filling in each instance the space between the shaft 100 and the central face of the pole piece, said pole pieces being removable to allow said coils to be removed as units from said core.

In testimony whereof, I hereunto subscribe my name this 14th day of November, 1918.

ALEXANDER H. HYNDMAN.
